UNITED STATES PATENT OFFICE.

SAMUEL LEVEY, OF DETROIT, MICHIGAN.

DESIGN FOR A CONTAINER.

Application filed May 16, 1921. Serial No. 470,004. Term of patent 3½ years.

To all whom it may concern:

Be it known that I, SAMUEL LEVEY, a citizen of the United States, residing at 10335 Mack Avenue, Detroit, in the county of Wayne, State of Michigan, have invented a new, original, and ornamental Design for a Container Intended Primarily for Pieces of Watermelon, of which the following is a specification, reference being had to the accompanying drawing, forming part thereof.

The figure is a perspective view of a container showing my new design. The colors are indicated conventionally as prescribed by the chart for draftsmen of the rules of practice of the United States Patent Office.

I claim:

The ornamental design for a container, as shown.

SAMUEL LEVEY.
